UNITED STATES PATENT OFFICE

169,123

DECORATIVE DISPLAY DEVICE

Robert L. Butzko, Bridgeport, Conn., assignor to Noma Electric Corporation, New York, N. Y., a corporation of New York

Application June 7, 1952, Serial No. 20,083

Term of patent 3½ years

(Cl. D29—1)

To all whom it may concern:

Be it known that I, Robert L. Butzko, a citizen of the United States, residing at Bridgeport, in the county of Fairfield and State of Connecticut, have invented a new, original, and ornamental Design for a Decorative Display Device, of which the following is a specification, reference being had to the accompanying drawing, forming part thereof.

Fig. 1 is a front elevational view of a decorative display device embodying my new design, and

Fig. 2 is a side elevational view of the same.

The back of the article is flat.

The characteristic features of my design reside in those portions shown in full lines.

I claim:

The ornamental design for a decorative display device, substantially as shown and described.

ROBERT L. BUTZKO.
